UNITED STATES PATENT OFFICE.

HENRY J. HORWICH AND EDMUND A. STEINMAN, OF CHICAGO, ILLINOIS.

BEDSTEAD LOCK AND STIFFENER.

Application filed June 7, 1920, Serial No. 336,968. Renewed December 26, 1922.

To all whom it may concern:

Be it known that we, HENRY J. HORWICH and EDMUND A. STEINMAN, both residing at Chicago, Cook County, Illinois, and both 5 citizens of the United States, have invented certain new and useful Improvements in a Bedstead Lock and Stiffener; and we do hereby declare the following to be a full, clear, and exact description of the invention, such as will enable others skilled in the art to which it appertains to make and use the same.

Our invention relates to metal bedsteads and in its general objects includes the stiffening of bedstead ends and the providing of 15 simple means constructed chiefly of sheet metal for affording the operative connections between various parts of the bedstead at the corner posts.

20 In one aspect, our invention aims to provide a socket constructed chiefly of sheet metal and adapted to be secured to a tubular bed post without employing screws or bolts, to provide sockets of this class which will 25 not rock on the posts to which they are secured and to use the sockets at the same end of the bedstead as means for connecting a stiffener to this bed end. For this last named purpose, our invention aims to construct these sockets so that a stiffener may 30 readily be secured directly to the same and preferably so that both webs of an angle-section stiffener may be secured directly to different parts of such a socket.

35 While our invention in its above named aspects may be employed with various bed spring or bed-bottom arrangements, it is particularly suited for use with bed constructions in which the bedstead ends cooperate with the side rails in forming a rigid frame and in which the bed-bottom is stretched in a separate frame supported by the side rails. For such beds, our invention aims to provide simple, strong and effective 40 side rail tips adapted to interlock with sockets of the type above mentioned, so as to afford a simple and inexpensive bedstead lock. Still further and also more detailed objects will appear from the following 45 specification and from the accompanying drawings, in which—

Fig. 1 is an enlarged and fragmentary vertical section through a bed post and through adjacent parts embodying our invention, 50 taken centrally of the post and longitudinally of the side rail of the bedstead.

Fig. 2 is a plan view of the same bedstead corner, taken from the top of Fig. 1.

Fig. 3 is a perspective view of the hook member or terminal on one end of a side 60 rail of the bedstead.

Fig. 4 is a perspective view of the socket or supporting member which is fastened to the bed post and which interlocks with the hook member or rail end piece of Fig. 3. 65

Fig. 5 is an elevation taken from the opposite side of Fig. 1, or from the top of Fig. 2.

Fig. 6 is a reduced view of the blank from which the sheet metal part of the socket of Fig. 4 is formed.

Fig. 7 shows the blank from which the hook member or rail end piece of Fig. 3 was formed.

Fig. 8 is a plan view showing the stiffener 75 interposed between the sockets carried by the posts on a bedstead end.

Fig. 9 is a plan view of a simplified form of socket adapted for use on a round post and without the stiffener. 80

In accomplishing the purposes of our invention after the manner illustrated in the drawings, we first secure to each post of the bedstead a socket member including a transverse pin, then mount a hook member upon 85 the adjacent end of the side rail of the bedstead and interlock the hooks of this member with the transverse pin on the socket member. Both of these members are preferably constructed of steel and preferably de- 90 signed so that they can be manufactured chiefly by punch press operations, thereby reducing their cost and insuring uniformity of the parts.

To use our invention in connection with 95 bedsteads having square sectioned tubular corner posts, we first punch an aperture 1 in each of the posts 2 along the face directed towards the side rail of the bedstead. Then we provide a corresponding aperture 3 in 100 the back 4 of the socket, which back is flat and rests squarely against the post 2 and which back has a pair of vertical webs 6 extending from its opposite edges towards the opposite end of the bedstead. These webs 105 are preferably parallel to each other and jointly carry a horizontal cross-bar 5 extending transversely of the webs and freely spaced from the said back. The socket as thus constructed of a single and formed 110 metal plate and a pin or cross-bar is held against the post of the bedstead with the

perforations 1 and 3 in alinement with each other, after which we insert the bent shank 7 of a sheet metal key through these alined perforations into the bore of the post 2 and 5 lock this key in position by means of a wedge 8 after the manner shown in Figs. 1 and 2. This wedge tends to draw the bent shank of the key further into the post, thereby drawing the enlarged heads 9 of the 10 key against the outer face of the back 4 of the socket so as to secure this socket firmly to the post with the cross-bar 5 in a fixed position predetermined by the location of the perforation 1 in the post.

15 To secure the desired rigidity in the corresponding end of the bedstead, which may be either the head end or the foot end, we desirably also connect the two sockets on the same end of the bedstead by a stiffener 20 25, so as to avoid the need of castings or other auxiliary fastenings for this purpose. With this in mind, we desirably form the blank for the socket after the manner of Fig. 6, so as to include a projecting lug 10 25 at the top of the web 6 which may be directed toward the companion socket when the parts are formed up. Then we bend this wing 10 at right angles to the adjacent web as shown in Fig. 4, so as to extend horizontally when the socket is in position. We also desirably punch another wing 11 from the same web 6 of the blank for the socket and bend this toward the companion socket so that it will extend vertically and at right 30 35 angles to this web. Then we rivet or bolt an angle steel stiffener 25 to the lugs 10 and 11 after the manner shown in Fig. 5, thereby affording a rigid connection between the companion sockets at the same end of the 40 bed, so that these sockets form the means of connecting the stiffener 25 to that end of the bedstead.

In punching the blank of Fig. 6 for the forked sheet metal part of the socket, we 45 desirably make the perforation 3 of the same size and rectangular shape as the perforation 1 in the post to which the socket is to be secured, thus permitting the wedge 8 to expand the key until its sides engage the side 50 walls of the perforations in both parts. Thus arranged, the key itself will tend to keep the socket from rotating about the latter as an axis, but in practice the strains 55 may be too great for the user to depend on the key to prevent an unsightly tilting or rocking of the socket on the post. We therefore desirably equip each socket with auxiliary means for preventing such tilting, as by providing each end of the blank of 60 Fig. 6 with wings 12 and 13 adapted to be bent in the opposite direction from the webs 6 and so spaced as to engage opposite sides of the adjacent post. Thus constructed, it 65 will be evident from Fig. 4 that the sheet metal part of our socket is substantially

H-shaped in its plan view (except for the wings to which the stiffener is fastened), with the upper part of the H formed by two pairs of lugs spaced vertically along the adjacent post when the socket is in position. 70 These pairs of lugs therefore straddle widely spaced parts of the post and securely hold the socket against rocking, although requiring no further fastening elements of any kind for this purpose. 75

To interlock the side rails of the bedstead with such sockets, we equip each end of each rail with a hook member or end piece designed to hook over the horizontal cross-bar 5 on an adjacent socket. We also prefer- 80 ably make the extreme hook portions of such a length that the tip of the hook in each case engages the back 4 of the socket with which it is used, thereby securing the firmly wedged interlocking which is more 85 fully described in our copending application for a U. S. patent on a bedstead lock, filed June 7, 1920 as Serial No. 386,967. This hook member or rail end piece is desirably formed from a single piece of sheet 90 metal blanked as shown in Fig. 7 and having its ends 26 overlapped after the manner of Fig. 3 and suitably secured to each other, as by a rivet 27, thus forming a tube of rec- 95 tangular cross-section. Then the tip of the side rail 28 (which is desirably made of angle steel) has both webs riveted to the re- 100 sulting tube, thereby insuring a rigid uniting of these parts, while the securing of the ends 26 to each other prevents any strain 100 from opening out the tube or spreading its sides apart.

However, while we have heretofore de- 105 scribed our invention in a desirable embodiment adapted for use with bedsteads having square sectioned hollow posts and angle sec- 110 tioned side rails, we do not wish to be limited to the details of the construction and arrangement thus disclosed. Obviously, va- 115 rious additions, omissions and other changes might be made without departing from the spirit of our invention or from the appended claims. For example, the same arrangement of connecting members carried by the side rails of the bedstead may be used in connec- 115 tion with round posts, and the latter need not necessarily have the sockets on the same connected by stiffeners. Thus, Fig. 9 shows a socket having a back curved to fit a round post and designed for use without any such 120 stiffener as that shown in Figs. 5 and 8.

We claim as our invention:

1. In a bedstead, side rails having end members formed of metal pieces of tubular rectangular cross-section the sides of which are formed with hooks and the bottoms of which are formed of the ends of the pieces, said ends being overlapped and secured to each other, and an end member having pins to engage the hooks. 125 130

2. In a bedstead, a pair of posts, a socket for each post having a back and having side wings between its top and bottom extending outwardly from the back, the ends of the 5 sides of the back being bent outwardly in a direction opposite to that in which the wings extend to form an upper and a lower pair of flanges which engage the post, a cross-pin borne by the wings, the inner wing 10 of each socket having an extension at its top extending outwardly in a horizontal plane and having a struck-out member extending vertically and underlying the extension, and an angle-bar secured to the 15 extensions and struck-out members respectively of the sockets.
3. In a bedstead, a corner post, a socket member having a back secured to the post and having side wings, a cross-pin secured 20 to the wings, and a side rail having a tubular end member of rectangular cross-section the sides of which member are formed with hooks and the bottom of which is formed of the ends of the member overlapped 25 and secured to each other, the edges of said overlapped ends and the edges of the sides and top of the end member being in the same plane whereby when the hooks are engaged with the cross-pin said edges
- will engage and be braced by the back of 30 the socket member and the sides of the tubular member will engage the side wings of the socket member.
4. In a bedstead, a corner post, a socket member having a back and side wings be- 35 tween the top and bottom of the back, the back having an upper and a lower pair of flanges located respectively above and below the side wings and engaged with the post to brace the socket member, a cross-pin 40 connected to the wings, and a side rail having a tubular end member of rectangular cross-section the sides of which member are formed with hooks and the bottom of which is formed of the ends of the member over- 45 lapped and secured to each other, the edges of said overlapped ends and the edges of the sides and top of the end member being in the same plane whereby when the hooks are engaged with the cross-pin said edges 50 will engage and be braced by the back of the socket member and the sides of the tubular member will engage the side wings of the socket member.

Signed at Chicago, Illinois, June 4th, 55
1920.

HENRY J. HORWICH.
EDMUND A. STEINMAN.
